(57) **CLAIM**

The ornamental design for a travelling body for construction machine as shown and described.

DESCRIPTION

FIG. 1 is a first perspective view of a travelling body for construction machine showing my new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a right side view thereof;

FIG. 8 is a top view thereof;

FIG. 9 is a partially enlarged first perspective view thereof;

FIG. 10 is a partially enlarged second perspective view thereof;

FIG. 11 is a partially enlarged third perspective view thereof;

FIG. 12 is a partially enlarged fourth perspective view thereof;

FIG. 13 is a partially enlarged front view thereof;

FIG. 14 is a partially enlarged rear view thereof; and,

FIG. 15 is a partially enlarged top view thereof.

The broken lines shown in FIGS. 1-15 that contain lightly shaded areas represent unclaimed portions of the traveling body for construction machine.
